UNITED STATES PATENT OFFICE.

JACOB S. LOWE AND JOHN H. LEITER, OF SHELBY, OHIO.

COMBINATION-RULER.

SPECIFICATION forming part of Letters Patent No. 232,988, dated October 5, 1880.

Application filed June 16, 1880. (No model.)

To all whom it may concern:

Be it known that we, JACOB S. LOWE and JOHN H. LEITER, of Shelby, in the county of Richland and State of Ohio, have invented a new and Improved Combination-Ruler, of which the following is a specification.

The object of this invention is to provide an improved device for facilitating mechanical drawing.

10 The invention is especially designed for schools, and is also useful to the mechanical draftsman and others; and it consists of a series of rulers having uniform scales of inches and fractions of inches adjustably suspended 15 on a horizontal rod, which is fixed in a head-board on the top of a blackboard or on a desk, said rulers being arranged in such a manner that by means of them geometrically-correct drawings of all kinds can be made.

20 Figure 1 is a front elevation of the device. Fig. 2 is an elevation of a ring used in the device, with a portion broken away to exhibit other parts.

Similar letters of reference indicate corresponding parts.

In the drawings, A represents the head-board, upper edge of a blackboard, or top of a desk. B is a metallic rod, bent at right angles at the ends, and driven into the desk, 30 blackboard, or head-board A, so that ample room shall be left between said board or desk A and the rod B for the free movement of the rings c c along said rod B, while beneath the rod B, on the board or desk A, a scale of inches 35 and fractions of an inch is marked, as shown at A'.

The attachment D consists of a piece of webbing or other flexible material, a, fastened, by means of glue, rivets, or other convenient device, to one end of the ruler b, while through the double strengthened end of said tip a is fastened a ring, c, that slides on the horizontal rod B, said ring c being constructed of metal covered with cloth, leather, or other substance that permits said ring c to move noiselessly 45 along the rod B.

The object of the flexible tip a is to permit the ready adjustment of the ruler b and its attached ruler d to a slate, copy-book, or sheet 50 of paper.

The ruler b is longitudinally slotted, as shown

at f, and in said slot f the ruler d is movably secured by means of the pin or set-screw g, so that said ruler d can be fixed at any desired angle relative to the ruler b, and so that said device D may be moved in either direction across the face of the desk, board, book, or slate.

The attachment E resembles the attachment D in the respect that the ruler h is the same 60 as the ruler b; but the adjustable ruler k is slotted, as shown at k', and secured in the slot of the ruler h by the thumb-screw l, so that the two rulers h k together form a compound slotted ruler, adjustable at any angle, the 65 thumb-screw l serving to hold the ruler k in any relative position with the ruler h. In the attachment E the ring c' encircles the rod B, and the ring n connects the ruler g, by means of the flexible tip o, to the said ring c', so that 70 the said attachment E has a maximum freedom of movement.

Another attachment, F, is shown, in which the single ruler p is secured and restrained in a vertical position on the rod B by means of a 75 screw-eye q.

All the rulers herein shown have uniform scales or graduations of inches upon them; hence all lines, angles, and drawings made by means of them are exact.

The head-board A is of especial use on sign-painters' and designers' tables for laying out letters, scrolls, and ornaments with the attachments; but said head-board A, as a separate board, is ordinarily omitted on school-desks and 80 blackboards, the rod B and its attachments D E F being secured directly upon said desk or blackboard, (represented by the board A,) and the scale A' being marked on said blackboard or desk, just in front of the rod B.

For a blackboard, desk, or table a strip of paper with a scale of inches printed thereon can be pasted or glued to the edge just below the rod B, instead of the printed scale on the head-board A; and a ring on the rod B, having 95 a string attached, may be used to slip along said rod B to assist in drawing horizontal lines, circles, &c.

Having thus described our invention, we claim as new and desire to secure by Letters 100 Patent—

1. In a ruler, the combination of the gradu-

ated board A, having rod B and the attachments D E, connected therewith by the flexible pieces a and slide-rings c, as shown and described.

5 2. In a combination-ruler, the combination, with the rod B and scale A', of the slotted ruler b, provided with flexible tip a and ring c, and ruler d, provided with set-screw or pin g, substantially as herein shown and described.

10 3. In a combination-ruler, the combination,

with the rod B and scale A', of the slotted ruler b, provided with flexible tip a and rings c' n, and slotted ruler k, provided with thumb-screw l, substantially as herein shown and described.

JACOB S. LOWE.
JOHN H. LEITER.
